TANK RACK

John H. Morcom, Long Beach, Calif.

Application October 3, 1949, Serial No. 5,279

Term of patent 7 years

(Cl. D52—2)

To all whom it may concern:

Be it known that I, John H. Morcom, a citizen of the United States, residing at Long Beach, in the county of Los Angeles and State of California, have invented a new, original, and ornamental Design for a Tank Rack, of which the following is a specification, reference being had to the accompanying drawings, forming a part thereof.

In the accompanying drawing:

Fig. 1 is a top plan view of a tank rack, showing my new design;

Fig. 2 is a side elevation thereof and showing in broken lines a pair of tanks in supported position for illustrative purposes only;

Fig. 3 is an end view, and

Fig. 4 is a bottom plan view.

Fig. 5 is a fragmentary, enlarged section taken on line 5—5, Fig. 2, and

Fig. 6 is a fragmentary, enlarged section taken on line 6—6, Fig. 1.

I claim:

The ornamental design for a tank rack as shown and described.

JOHN H. MORCOM.
